Design No. 18,318, dated May 15, 1888.

2117

2117

UNITED STATES PATENT OFFICE.

ELLEN MORAN, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,318, dated May 15, 1888.

Application filed April 30, 1888. Serial No. 271,348. Term of patent 3½ years.

To all whom it may concern:

Be it known that I, ELLEN MORAN, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a basque and a round walking-skirt. The skirt displays a flat drapery falling to the edge all round; long oval panniers meeting at the belt at the center of the front, flaring toward the sides, and exhibiting draping plaits in the top near the front and back edges; full back draperies flaring at their back edges and displaying draping plaits

in the top. The basque exhibits close-fitting fronts opening from the shoulders over a full vest that displays shirrings at the neck, a belt-strap at the waist-line, and a drooping effect at the bottom; a close-fitting back pointed at the center of its lower edge; revers passing down the front edges of the fronts, coat-sleeves, and a standing collar.

What I claim as my invention, and desire to secure by Letters Patent, is—

The design for a lady's costume, as shown in the engraved prints accompanying this specification.

ELLEN MORAN.
